Primary Examiner — Keli L Hill
Assistant Examiner — Sara S Sahneh(57) **CLAIM**

The ornamental design for fastener set, as shown and described.

DESCRIPTION

FIG. 1 is a front, top, left perspective view of a fastener set showing my new design;

FIG. 2 is a left side view of the fastener set of FIG. 1;

FIG. 3 is a right side view of the fastener set of FIG. 1;

FIG. 4 is a front view of the fastener set of FIG. 1;

FIG. 5 is a rear view of the fastener set of FIG. 1;

FIG. 6 is a top view of the fastener set of FIG. 1; and,

FIG. 7 is a bottom view of the fastener set of FIG. 1.

The broken line showing of fastener set is included for the purpose of illustrating environmental structure while all other lines illustrate portions of the fastener set; the broken lines form no part of the claimed design.
